DESIGN FOR A CIGARETTE LIGHTER

Charles W. Smith, Rockville Centre, N. Y.

Application October 31, 1947, Serial No. 142,237

Term of patent 3½ years

(Cl. D43—27)

To all whom it may concern:

Be it known that I, Charles W. Smith, a citizen of the United States of America, residing at 45 Raymond Street, Rockville Centre, N. Y., in the county of Nassau and State of New York, have invented a new, original, and ornamental Design for Cigarette Lighters, of which the following is a specification, reference being had to the accompanying drawing, constituting a part thereof.

Fig. 1 is a plan view of a cigarette lighter, showing my design.

Fig. 2 is an elevational view.

I claim:

The ornamental design for a cigarette lighter, substantially as shown.

CHARLES W. SMITH.
